UNITED STATES PATENT OFFICE

PAUL TURLUR, OF WATTRELOS, FRANCE.

ARRANGEMENT FOR DOBBY AND JACQUARD MECHANISMS WEAVING WITH OPEN SHED.

1,102,826.

Specification of Letters Patent.

Patented July 7, 1914.

Application filed December 4, 1912. Serial No. 734,861.

To all whom it may concern:

Be it known that I, PAUL TURLUR, citizen of the French Republic, residing at Wattrelos, in the Department of Nord, France, have invented a certain new and useful Improved Arrangement for Dobby and Jacquard Mechanisms Weaving with Open Shed, of which the following is a specification.

10 This invention relates to improvements in dobbay and jacquard mechanisms which are especially adapted for weaving with open shed.

In my application, Serial No. 625,094, filed May 4, 1911, I have shown and described a form of mechanism adapted to control the movements of the movable jack which is adapted to be connected to the harness of a heddle frame, and the present invention relates to improvements in the mechanism for raising and lowering the jack as well as locking it in its raised or lowered position, which mechanism is of a simple and compact construction and capable of locking the jack in its raised or lowered position without the use of the extra bolts, pawls and other parts which have been heretofore used for this purpose.

With this and other objects in view, which will be apparent from the description, my invention consists in the constructions and combinations of parts which will be hereinafter set forth and particularly pointed out in the claims.

35 In the accompanying drawings, the figure represents somewhat diagrammatically a jack having associated therewith a movable jack-hook and locking members embodying the features of my invention.

40 In the drawings, 1 designates the rigid jack which is adapted to slide vertically in the guides 2, the jack being adapted to be connected to the usual form of harness of a heddle frame (not shown) in the usual manner. Projecting laterally from the jack 1 adjacent its lower end is a lug 3 carrying a pivot 4 upon which a T-shaped member 5 is mounted, which is provided with teeth 6 and 7 at the ends of its lateral arms.

45 A jack-hook 9 is pivotally connected to the member 5, as at 8, and has an oscillatory lateral movement as well as a vertical movement, its upper end being normally urged toward the right by the compression spring 10. A locking lever 11 is provided at its

upper end with spaced notches 13 and 14 which are respectively adapted to co-act with the teeth 6 and 7 to hold the jack 1 in either its raised or lowered position, the upper end of the locking lever being normally urged against the teeth 6 and 7 by means of the spring 12. The jack-hook 9 is raised or lowered by means of any of the well known constructions used in looms for this purpose and in the specific embodiment of the invention shown, a disk 15, which is provided with arms mounted parallel to the axis of rotation of the disk and adjacent the periphery of the same, is rotated continuously in such a manner that the arms 70 act as eccentric bars and serve to lower the jack 1 when the jack-hook 9 is engaged, the jack-hook being provided with a laterally projecting hooked portion 18 which is normally thrown into the path of one of the arms 15 by means of the spring 10. In the same manner the jack is raised by means of the second disk 16 provided with similarly mounted arms, which is driven in the same direction as the disk 15, as is clear 75 from the arrows designating the rotation of these two disks. The movable jack-hook 9 has projecting laterally from its extreme upper end a second hook 19 which is adapted to be engaged by the arms carried by the 80 disk 16.

17 designates the needle of the jacquard mechanism which enters the perforations in the ordinary form of card (not shown), which needle serves to press the movable 90 jack-hook 9 against the action of the spring 10 toward the left, so that the hook 19 will engage the arm 16 when the end of the needle 17 is pressed backwardly, which occurs when it meets a solid portion of the card 95 (not shown).

Mode of operation:—The position of the parts of the mechanism illustrated in the drawing shows the instant at which needle 17 has entered a perforation of the card. 100 By dint of the action of spring 10 the movable part or head 9 places itself in the course of disk 15 and one of the arms or bars of this disk will strike against projection 18 provided for this purpose, so that head 9 105 is first lowered with regard to stave 1, whereupon part 5 is shifted accordingly and removes tooth 6 from notch 13 of the locking device so that the whole of the hook is liberated. The latter will then owing to 110

the continued action of disk 15 be lowered and will cause the heddle to be raised which it controls. When it has arrived at the end of its path projection 18 of the head 9 will be liberated owing to the rotation of the arm on its axis, while the whole hook device is supported in its new position by the engagement of tooth 7 beneath notch 14 of the locking lever. As long as the perforations in the cards correspond with the needle 17 of this hook, the position of the latter will be maintained and the shed will thus be kept open. As soon as the needle 17 no longer meets with a perforation, it is repelled and bears against the movable head 9, so that the latter is pushed back and another projection 19 provided in the same for this purpose places itself in the path of the arm of disk 16. At this moment the head 9 will be raised, part 5 is shifted and repels by tooth 6 the locking lever 11 which frees tooth 7, so that the whole contrivance is unlocked and removed with disk 16 as the latter continues its rotation. At the end of its course projection 19 of the head 9 will be liberated owing to the rotation of the arm of the disk, while tooth 6 engages in notch 13 of locking lever 11, so that the hook will be locked in this position until new perforations will again cause needle 17 to be shifted.

What I claim is:

1. In a dobby mechanism for looms, a movable jack adapted to be connected to the harness of a heddle frame, a member pivotally connected to said jack, a locking lever having interengaging parts for locking the jack in either its raised or lowered position,

a jack-hook pivotally connected to the end of said member, and means for raising and lowering said jack-hook whereby the members is first released from locking engagement with said locking lever and thereafter the jack-hook and jack are both bodily moved. 45

2. A dobby mechanism for looms, a movable jack adapted to be connected to the harness of a heddle frame, means for moving and holding said jack in its raised or lowered position comprising a member pivotally mounted on the jack, a locking lever, said member and locking lever having interengaging parts to hold the lever in its raised or lowered position, a jack-hook pivotally mounted on said member, separate means for engaging with said hook to raise and lower the same whereby the raising or lowering of said jack-hook will first move one of said interengaging parts carried by the member out of engagement with the locking lever and the other of said parts into a position to be engaged by the locking lever after it has been carried to its moved position and thereafter move the jack bodily to its moved position, and means controlled by the needle of a jacquard mechanism for controlling the engagement of said jack-hook with the means for raising and lowering it. 65

In testimony whereof I affix my signature 70 in presence of two witnesses.

PAUL TURLUR.
